PARACHUTIST SHOE

Ralph W. Jennings, Cambridge, Mass.

Application April 10, 1942, Serial No. 438,365

2 Claims. (Cl. 36—2.5)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

The present invention relates to shoes, but more particularly to shoes used by parachutists of the armed forces.

A shoe, to be adapted for this particular use, must be light, flexible and yet be constructed in some manner to fully support and protect the ankles and feet of the jumper.

Heretofore, shoes of this type have been constructed of very flexible leather which has been strong enough to support the ankle and yet have some resiliency, but these shoes, while being well adapted for jumping purposes, have been very uncomfortable for marching.

Therefore, the present invention has been developed as an overshoe adapted to be worn over the usual high or low shoe worn at all times by the armed forces. However, in order to support and protect the wearer some means had to be incorporated in the shoe to adapt it for the purpose for which it is intended.

For this reason an important object of the invention is to provide a shoe having a well-protected and heavy box toe adapted to have a stiffening member incorporated therein to protect the toes of the wearer.

Another object is to provide supporting means in the uppers to protect the ankles of the wearer, the upper being so constructed that it is higher than the usual high shoe but not extending as high on the leg of the wearer as the well-known "high-top" or boot shoe.

Another object of the invention is to provide protecting means for the tarsus or ginglymus joint which lies between the tibia and fibula and the astragalus of the wearer's leg.

Another object of the invention is to provide a soft and highly resilient inner sole which is adapted to soften the shock of the landing of the wearer from the heights from which the jump is made even though his descent is softened by the parachute.

Another object of the invention is to provide two closures for the shoe, one of which uses the slide type fastener for a quick removal of the shoe from the wearer's foot and the other the lace type, which permits the wearer to lace the shoe in such a manner that it will fit the wearer's ankle snugly and thus prevent chafing or any looseness around the ankle which would decrease, by irritation, the maximum efficiency of the wearer.

A further object of the invention is to provide a shoe which is generally of a new and improved construction, which may be manufactured at a low and reasonable cost and is more comfortable than shoes previously designed for this particular purpose.

Its low cost is also a material improvement because the wearer may remove and abandon the shoes after the jump without sacrificing any of his efficiency or placing a great loss upon the supplies of the Government.

Other objects of the invention and the various advantages and characteristics of the shoe will be apparent from the fully detailed description and the drawings which accompanying and form a part of this specification and in which like reference numerals denote corresponding parts throughout the several views.

Fig. 1 is a perspective of the shoe embodying the invention.

Fig. 2 is a side elevation of the shoe.

Fig. 3 is a diagrammatical sectional view on the line 3—3 of Fig. 2.

Fig. 4 is a longitudinal vertical sectional view of the shoe taken through the center on the line 4—4 of Fig. 1, and

Fig. 5 is a diagrammatical sectional view on the line 5—5 of Fig. 2.

Referring now to the drawings, numeral 10 indicates as a whole the illustrated embodiment of the invention, having the upper part divided into two side portions 11 and 12. A folding tongue 13, which is a continuation of the lining 14, is made sufficiently wide to close the gap between the side portions 11 and 12 and is adapted to fold back at the side of the leg when the shoe is properly fastened.

The side portions 11 and 12 are adapted to be closed by any well-known fastener means 15 having a slide 16 which has a tape or leather tie 17 connected thereto to give a better gripping means for the hands of the wearer.

There is located adjacent to the fastening means 15 a second fastening means 18 which is closed by means of the ordinary shoe lace 19. This second fastening means permits the shoe to be adjusted to snugly fit the foot and leg of the wearer and once adjusted need not be untied unless the shoe or lace should stretch or the size or contour of the foot and ankle of the wearer should change.

In order to brace the ankle there are incorporated in the side portions 11 and 12 strips of fiber 20 which are interposed substantially longitudinally between the lining and the outer por-

tion of the shoe and since they are completely covered by the outer portion they form bulges 21 on the exterior of the side portions. There is also inserted between the lining and both sides of the exterior of the shoe a protector 22, consisting of a circular piece of fiber which forms a shield or guard of a hard substance to protect the ginglymus joint of the wearer's foot. The protector 22 is interposed between a lining 14 and an inner patch 14' of the same material, which prevents the protector from being loosened from the lining 14 by the constant insertion and removal of the wearer's foot. Thus, there is formed on the exterior of the shoe a bulge or protuberance 23 which conforms to the size and shape of the protector 22. It will be seen, therefore, that when the shoe is on the foot the hard protectors will protect from injury, to a certain extent, the ginglymus joint of the foot.

Additional protection is afforded to the wearer's foot by a heavy fiber protector 24 in the toe 25 of the shoe 10.

In order to prevent shock when landing, a heavy sponge or foam rubber inner sole 26 is provided in the shoe and has been found to absorb more of the shock than the shoe previously used for this purpose.

The present invention has been designed to use rubber, either natural or synthetic, but it is to be understood that the material used is not to be restricted to the use of rubber, since other materials may be used in lieu thereof.

While the invention has been shown and described in a preferred form, various changes and modifications may be made without departing from the principles of the invention, the scope

of which is to be determined by the appended claims.

Having thus described the invention, what is claimed as new and desired to secure by Letters 5 Patent is:

1. A parachutist's shoe, comprising an outer portion, a reinforced toe, a lining, longitudinal reinforcements and hard substance ankle protectors interposed between the lining and the outer portion, said reinforcements and said ankle protectors adapted to protect the ankle and ginglymus joint of the foot, a slide-fastening unit for securing together adjacent parts of the outer portion, a lace-fastening unit parallel to the path 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290

1. A parachutist's shoe, comprising an outer portion, a reinforced toe, a lining, longitudinal reinforcements and hard substance ankle protectors interposed between the lining and the outer portion, said reinforcements and said ankle protectors adapted to protect the ankle and ginglymus joint of the foot, a slide-fastening unit for securing together adjacent parts of the outer portion, a lace-fastening unit parallel to the path of said slide-fastening unit and a cushioning inner sole of yielding material applied over and secured to the outer sole of the shoe.

2. A parachutist's shoe, comprising an outer portion, a reinforced toe, a lining, longitudinal reinforcements and hard substance ankle protectors interposed between the lining and the outer portion, said reinforcements and said ankle protectors adapted to protect the ankle and ginglymus joint of the foot, a slide-fastening unit for securing together adjacent parts of the outer portion, a continuation of the lining adapted to form a tongue to cover the opening between the outer portions, said tongue adapted to lie in a substantially flat position when the slide-fastening unit is completely closed, a lace-fastening unit parallel to the path of said slide-fastening unit and a cushioning inner sole of yielding material applied over and secured to the outer sole of the shoe.

RALPH W. JENNINGS.
